TOY

Chester A. Pridham, Chatham, N. J.

Application April 11, 1936, Serial No. 73,818

9 Claims. (CL. 212—79)

My invention relates to improvements in toys. One of the objects of my invention is to provide an improved construction for a toy embodying an overhead travelling carriage and which is adapted particularly for carrying material from one point to another and dumping it, and in which provision is made for controlling the various movements from a single remote point, including the action of dumping the load at the desired place.

Another object of my invention is to provide an improved toy of the character referred to which is simple and rugged in construction, reliable in operation, and which can be made up for sale in the form of a kit and readily installed at any convenient place.

Another object of my invention is to provide an improved toy of the character referred to in which all of the required movements or actions for picking up material, transporting it from one point to another, and dumping the load, can be controlled conveniently from a portable control unit which can be moved to different positions without disturbing the rigging.

Another object of my invention is to provide an improved toy of the character referred to which is educational and instructive, and whose operation can be readily understood and performed by children.

Other objects and advantages will hereinafter appear.

For the purpose of illustrating my invention, an embodiment thereof is shown in the drawings, wherein

Figure 1 is a simplified, elevational view, partly in perspective, of a toy constructed and operating in accordance with my invention;

Fig. 2 is an enlarged sectional view, the section being taken on the line 2—2 in Fig. 1;

Fig. 3 is an elevational view of the control unit, partly broken away and looking toward the right in Fig. 1;

Fig. 4 is an elevational view, partly broken away and looking toward the right in Fig. 3;

Fig. 5 is a plan view of Fig. 3;

Fig. 6 is a perspective view showing the manner of using a scoop bucket for conveying the material;

Fig. 7 is an enlarged detail view, partly in section, showing the means and method used for conveying sticks of wood and the like and dumping such a load;

Figs. 8 and 9 are views similar to Figs. 3 and 5, respectively, showing a modification;

Fig. 10 is an enlarged sectional view, taken on the line 10—10 in Fig. 9;

Fig. 11 is an enlarged detail view showing a form of a grab bucket and the manner of using the same;

Fig. 12 is a view similar to Fig. 11, partly broken away, showing the bucket in Fig. 11 opened to discharge the load; and

Fig. 13 is a sectional view, the section being taken on the line 13—13 in Fig. 12.

With reference to Fig. 1, the reference numeral 10 designates a part in the form of a supporting overhead carriage provided with trolleys 11 for running along a track comprising a steel wire 12 stretched between the fixed points 13 and 14.

A part in the form of a pulley block 15 of conventional design is suspended from the carriage 10 by a lift line 16 fixed at one end thereof to this block at 17. As shown, the line 16 passes around the pulley 18 of the pulley block and around the pulleys 19 and 20 fixed to the underside of the carriage 10, and thence around a fixed pulley 21 to a spool 22 which may be rotated by turning a crank 23.

For the purpose of causing travel of the carriage 10 along the track 12, a line 24 is fixed at one end thereof to the carriage at the point 25 and extends around a fixed pulley 26 and thence around a fixed pulley 27 to a spool 28 which may be rotated by turning a crank 29.

A trip line 30 carries at one end thereof a hook 31 and passes through an eyelet 32 with which the pulley block is provided, through an eyelet 33 with which the carriage is provided, around a fixed pulley 34, and thence to a spool 35 supported at its ends by elastic bands 36. These elastic bands are stretched and twisted, as represented, and are fixed to the sides 37 of a box 38 for supporting and containing the various control parts as a portable unit.

The spools 22 and 28 are, as shown, rotatably supported by the top 39 of the box, which is provided with an opening 40 through which the trip line 30 passes.

The spool 22 is held against rotation by a friction brake element 41 pivotally mounted at 42 and held pressed against the spool by a spring 43. The spool 28 is held against rotation by a similar friction brake element 44 pivotally mounted at 45 and held in engagement with this spool by a spring 46.

In Fig. 1 the apparatus is shown in use with a grab bucket comprising complementary parts 47 and 48 pivotally connected together at their respective adjacent corners by a relatively stiff wire 55.

49 which is bent around at its center to form an eyelet 53 to receive a lift hook 51 with which the pulley block is provided. A flexible member in the form of a coil spring 52 extends across the wire 49 and is connected at its ends to the parts 54 and 48, as more clearly shown in Fig. 2. In operation, the trip hook 31 is hooked about the spring 52, as shown.

From the foregoing it will be seen that the carriage 10 can be caused to travel along the track 12 to the right by rotating the crank 23 to wind up the travel line 24 on the spool 28. By rotating the spool 28 in the opposite direction to pay out the travel line 24, the carriage 10 travels 15 to the left along the track 12 by reason of the force provided by the weight of the pulley block 15. While this weight is sufficient for this purpose, the weight of the bucket or other carrying device, as well as any load which is being transported at the time, adds an additional force to 20 cause this movement. This force is generally sufficient to cause lefthand movement of the carriage 10 along the track by merely releasing the brake 44 to permit free rotation of the spool 28 to 25 pay out the line 24.

The pulley block and its load is raised by turning the crank 23 to wind up the lift line 16 on the spool 22. Lowering of the pulley block and its load, due to the weight of the parts, can be 30 caused by merely releasing the brake element 41 to permit rotation of the spool 22 to pay out the lift line 16. Assuming that the parts are in the full-line position shown in Fig. 1, the load can be carried to the dash-line position shown by 35 rotating the cranks 23 and 29 in the proper directions either successively or simultaneously, after which the load can be dumped by pulling in on the trip line 30 to cause pivotal movement of the bucket parts with respect to each other, as shown.

40 The tension of the springs 43 and 46 is not such as to prevent turning of the cranks 23 and 29 as might be required, but is sufficient to hold the spools 22 and 28 against rotation when the cranks are released.

45 By turning the crank 23 to wind in on the lift line 16 until the pulley block is raised to engage the carriage 10, and continuing this rotation, the carriage is caused to move to the left along the track 12, during which time the spool 28 is rotated to pay out the line 24. The lefthand movement of the carriage 10 is therefore caused either by turning the crank 29 only or by turning the crank 23 only in the proper direction, as explained.

50 An important feature of my improved construction resides in the means for keeping the trip line 30 taut irrespective of any movements of the carriage 10 or the pulley block 15 which might take place. This means comprises the spool 35 mounted as explained. That is, the arrangement is such that as the pulley block and its load is raised, or as the carriage 10 moves to the left, the spool 35 is rotated to take up on the lift line 30 by reason of the stretch and twist of the elastic bands 36. As the pulley block and its load is lowered, or as the carriage 10 moves to the right, the spool 35 is free to rotate to pay out the trip line 30, during which rotation the twist and stretch of the elastic bands 36 are increased.

55 In using the grab bucket 47, 48 to handle sand, for example, it is lowered on the material and the lift line 16 paid out to make this line a little slack. The trip line 30 is then drawn in at the control unit 38 to open the bucket and raise it 60 over the load, after which the trip line is re-

leased to permit the bucket to drop and the bucket parts to grab into the sand. The crank 23 is then turned to raise the pulley block which causes the bucket parts to close and pick up some of the material. When the load has been moved to the desired point, it is dumped by 5 pulling in on the trip line 30 as explained.

In using the scoop bucket 54 shown in Fig. 6, it is hung from the lift hook 51 as shown, and the lift hook 31 hooked into an eyelet 55 with which this bucket is provided at the bottom thereof. By proper manipulation of the cranks 23 and 29 and the trip line 30, as will be well understood, a load can be picked up by the bucket 54 and then transported to the desired point. By then pulling 10 in on the trip line, the bucket is tilted to the dash-line position as shown to dump the load. 15

In handling sticks of wood and the like, a chain 56 provided at one end thereof with a ring 57 is attached to the lift hook 51 by this ring. 20 The other end of the chain is provided with a hook 58 and is placed about the load and the hook 58 caught about the chain as shown. The lift hook 31 is then caught about the hook 58. When the load has been moved to the desired point, the 25 trip line 30 is pulled in slightly to disengage the hook 58 from the chain, whereupon the load is released. The trip line is then paid out until the hook 31 is disengaged from the hook 58, after 30 which this line is released to permit the spool 35 to wind it in until the hook 31 catches in the eyelet 32 with which the pulley block is provided and through which the trip line passes.

In the modification shown in Figs. 8 and 9, the various parts are designated by the same 35 reference numerals, but with the suffix "a", as the respective and corresponding parts in Figs. 3, 4 and 5. In Figs. 8 and 9, the cranks 23a and 29a are separately mounted, as shown, and are geared to the spools 22a and 28a by gears 60, 61, 40 62 and 63. A gear 64 is fixed on a crank 65 which is journaled in a bracket 66 and is movable longitudinally to place the gear 64 into or out of mesh with the gears 61 and 63. A spring 67, compressed between the bracket 66 and a 45 collar 68 fixed on this crank, operates to move the latter to the full-line position shown where- 50 at the gear 64 is out of mesh with the gears 61 and 63. The arrangement and relation of the various parts are such that by moving the gear 55 64 into mesh with the gears 61 and 63, and then by turning the crank 65 only, the spools 22a and 28a are caused to rotate simultaneously to move the carriage 10 along its track and also to pay 55 out or take in on the lift line 16a, as the case 60 might be, so that the pulley block and its load moves substantially parallel to the track 12. When the crank 65 is released the gear 65 is moved out of mesh with the gears 61 and 63 by the spring 67.

65 Brake elements 41a and 44a, corresponding to, and operating in the same manner as the elements 41 and 44 respectively in Figs. 3, 4 and 5, are pivotally mounted at 42a and 45a and are spring-biased to rotate in the directions indicated by the arrows to engage the gears 63 and 61. The ends 41b and 44b of the elements 41a and 44a are shaped and disposed as more clearly shown in Fig. 10, in front of a collar 69 with which the crank 65 is provided. When the 70 crank 65 is pushed forward, therefore, both brakes 41a and 44a are released automatically as the gear 64 starts to mesh with the gears 61 and 63.

75 With the gear 64 out of mesh with the gears 61 75

and 63, the cranks 23a and 29a can be operated independently of each other in the same manner and for the same purposes as the cranks 23 and 29 in Figs. 3, 4 and 5.

5 Either of the brake elements 41a and 44a can be released without releasing the other, as might be desired.

The relative sizes of the gears are as shown in Figs. 8 and 9, to provide for a reduction from 10 the cranks 23a, 29a and 65 to the spools 22a and 28a.

For the purpose of guiding the travel and lift line in Figs. 3, 4 and 5, idler pulleys 70 and 71 are used as shown, and are attached to the 15 top 39 of the control unit by swivel connections of a conventional construction. Similar pulleys 70a and 71a are used in the same manner and for the same purpose in the construction shown 20 in Figs. 8 and 9.

20 The grab bucket shown in Figs. 11, 12 and 13 comprises the two complementary parts 72 and 73. Members 74 are connected rigidly to the part 72, and similar members 75 are connected rigidly to the part 73. A weight 76 is disposed 25 between the overlapping adjacent ends of the members 74 and 75 which are pivotally connected by a pin 77 which extends loosely through the weight 76. The weight 76 is provided with an eyelet 78 by which the bucket is suspended 30 from the lift hook 51 of the pulley block.

A flexible member 79, which may be a cord, chain or the like, is connected at its ends to the bucket parts 72 and 73. In using this bucket, the trip hook 31 is placed around the flexible 35 member 79.

In using this bucket, it is placed over the material to be picked up, and the trip line 30 is pulled in to open the bucket, as shown in Figs. 12 and 13. The pulley block is then lowered to 40 place the open bucket on the material, after which the trip line is released. The pulley block is then raised, which action causes pivotal movement of the bucket parts 72 and 73 together about the pin 77 as the center. As the bucket 45 parts are caused to move together in this manner, they grab into the material and pick up a load. The edge 80 of the bucket part 72 may be offset slightly as shown so that when the bucket parts are together it overlaps the complementary edge 81 of the bucket part 73 to prevent 50 material such as sand from leaking out between these edges of the bucket parts.

From the foregoing it will be seen that by reason of the arrangement and combination of 55 the parts, and the manner of rigging the various control lines with respect thereto, and supporting the control ends of these lines from a common support, the control unit 38 is provided which is portable and can be moved to different 60 positions without disturbing the rigging or making necessary any changes in the various connections. In this connection, I believe myself to be the first to provide a toy of the character described embodying an overhead carriage and 65 a pulley block suspended therefrom, in which there is a unit which can be moved to different positions without interfering with the rigging and from which all movements and operations of the various parts can be controlled.

70 It will be understood that various changes and modifications other than those described herein, can be made without departing from the spirit of my invention or the scope of the claims.

I claim as my invention:

75 1. In a toy of the character described, a part

in the form of a pulley block, a part in the form of a supporting overhead carriage for said block, a track element for said carriage, a travel line and a lift line and a trip line, said lift line being rigged to said parts and having one of its ends 5 fixed to one of said parts, a first spool for paying out or taking in said lift line to lower or raise said block with respect to said carriage, one end of said travel line being fixed to said carriage, a second spool for paying out or taking 10 in said travel line to cause said carriage to travel back and forth along said track element, said trip line being rigged to said carriage, means for keeping said trip line relatively taut irrespective of movement of said carriage in either direction along 15 said track and comprising a third spool and yieldable means urging said third spool for rotation in one direction, and means for rotating said first and second spools the weight of said pulley block and its associated 20 parts being sufficient to impart movement to said carriage toward the control-end of the rigging when said travel line is paid out.

2. In a toy of the character described, a part 25 in the form of a pulley block, a part in the form of a supporting overhead carriage for said block, a track element for said carriage, a travel line and a lift line and a trip line, said lift line being rigged to said parts and having one of its ends fixed to one of said parts, a first spool for paying 30 out or taking in said lift line to lower or raise said block with respect to said carriage, one end of said travel line being fixed to said carriage, a second spool for paying out or taking in said travel line to cause said carriage to travel back 35 and forth along said track element, said trip line being rigged to said carriage, means for keeping said trip line relatively taut irrespective of movement of said carriage in either direction along said track and comprising a third spool and yieldable means urging said third spool for rotation 40 in the direction to take in on said trip line, means for rotating said first and second spools, and portable means common with respect to said three spools for supporting the same and moveable bodily as a unit whereby the respective movements of said carriage and pulley block and said trip line can be remotely and selectively controlled from different positions said spool and said 45 yieldable means being entirely concealed within 50 said portable means.

3. In a toy of the character described, a part 55 in the form of a pulley block, a part in the form of a supporting overhead carriage for said block, a track element for said carriage, a travel line and a lift line and a trip line, said lift line being rigged to said parts and having one of its ends fixed to one of said parts, a first spool for paying 60 out or taking in said lift line to lower or raise said block with respect to said carriage, one end of said travel line being fixed to said carriage, a second spool for paying out or taking in said travel line to cause said carriage to travel back 65 and forth along said track element, said trip line being rigged to said carriage, means for keeping said trip line relatively taut irrespective of movement of said carriage in either direction along said track and comprising a third spool and means for urging rotation of said third spool in the direction to take in on said trip line, and 70 portable means disposed at one end of said track and being common with respect to said three spools for supporting the same for bodily movement as a unit whereby the respective movements of said carriage and pulley block and said trip 75

line can be remotely and selectively controlled from different positions, the weight of said pulley block and its associated parts being sufficient to impart movement to said carriage toward the 5 control-end of the rigging when said second spool is rotated to pay out said travel line.

4. In a toy of the character described, a part in the form of a pulley block, a part in the form of a supporting overhead carriage for said block, a track element for said carriage, a travel line and a lift line and a trip line, said lift line being rigged to said parts and having one of its ends fixed to one of said parts, a first spool for paying out or taking in said lift line to lower or raise 10 said block with respect to said carriage, said travel line being rigged with respect to said carriage and arranged when paid out or taken in on one side of said carriage to cause said carriage to travel back and forth along said track element, means for keeping said trip line relatively 15 taut irrespective of any movements of said parts and comprising a second spool and yieldable means for urging rotation of said second spool in the direction to take in on said trip line, and portable means disposed at one end of said track 20 and being common with respect to said spools for supporting the same for bodily movement as a unit whereby the respective movements of said carriage and pulley block and said trip line can be remotely and selectively controlled from different positions, the weight of said pulley block 25 and its associated parts being sufficient to impart movement to said carriage toward the control-end of the rigging when said travel line is paid out.

5. A toy comprising a part in the form of a pulley block, a part in the form of a supporting overhead carriage for said block, a track element for said carriage, a travel line and a lift line 40 and a trip line, said lift line being rigged to said parts and having one of its ends fixed to one of said parts, means for paying out or taking in said lift line to lower or raise said block with respect to said carriage, said travel line being rigged with 45 respect to said carriage and arranged when paid out or taken in on one side of said carriage to cause the same to travel back and forth along said track element, means for keeping said trip line relatively taut irrespective of any movements 50 of said parts, a bucket comprising complementary parts, means pivotally connecting said parts, said bucket being suspended from said pulley block by said connecting means, and a flexible element connected at its ends to the respective upper edges 55 of said bucket parts, said trip line being provided at one end thereof with a hook placed about said flexible element, the weight of said pulley block and its associated parts being sufficient to impart movement to said carriage toward the control-end of the rigging when 60 said travel line is paid out.

6. In a toy of the character described, a part in the form of a pulley block, a part in the form of a supporting overhead carriage for said block, a track element for said carriage, a travel line and a lift line and a trip line, said lift line being rigged to said parts and having one of its ends fixed to one of said parts, a first spool for paying out or taking in said lift line to lower or raise 65 said block with respect to said carriage, said travel line being rigged with respect to said carriage and arranged when paid out or taken in one side of said carriage to cause said carriage to travel back and forth along said track element, means for 70 keeping said trip line relatively taut irrespective 75

of any movements of said parts and comprising a second spool and yieldable means for urging rotation of said second spool in the direction to take in on said trip line, portable means disposed at one end of said track and being common with 5 respect to said spools for supporting the same for bodily movement as a unit whereby the respective movements of said carriage and pulley block and said trip line can be remotely and selectively controlled from different positions, a bucket 10 comprising complementary parts pivotally connected together and suspended from said pulley block, and means associated with said bucket for causing the same to open, one end of said trip line being provided with a means engaging said 15 bucket-opening means for operating the same.

7. In a toy of the character described, a part in the form of a pulley block, a part in the form of a supporting overhead carriage for said block, a track element for said carriage, a travel line 20 and a lift line and a trip line, said lift line being rigged to said parts and having one of its ends fixed to one of said parts, a first spool for paying out or taking in said lift line to lower or raise said block with respect to said carriage, one end of 25 said travel line being fixed to said carriage, a second spool for paying out or taking in said travel line to cause said carriage to travel back and forth along said track element, said trip line being rigged to said carriage, means for keeping 30 said trip line relatively taut irrespective of any movements of said parts and comprising a third spool and yieldable means urging said third spool for rotation in the direction to take in on said trip line, means for rotating said first and second spools, portable means common with respect to said three spools for supporting the same and moveable bodily as a unit whereby the respective movements of said carriage and pulley block and said trip line can be remotely and 40 selectively controlled from different positions, and yieldable braking elements associated respectively with said first and second spools for holding the same against rotation, the weight 45 of said pulley block and its associated parts being sufficient to impart movement to said carriage toward the control-end of the rigging when said travel line is paid out.

8. In a toy of the character described, a part in the form of a pulley block, a part in the form of a supporting overhead carriage for said block, a track element for said carriage, a travel line and a lift line and a trip line, said lift line being rigged to said parts and having one of its ends fixed to one of said parts, a first spool for paying out or taking in said lift line to lower or raise 50 said block with respect to said carriage, a second spool for paying out or taking in said travel line to cause said carriage to travel back and forth along said track element, said trip line being 55 rigged to said carriage, means for keeping said trip line relatively taut irrespective of movement of said carriage in either direction along said track and comprising a third spool and yieldable means urging said third spool for rotation in one direction, and means moveable to one position and operable in said position to rotate said first and second spools simultaneously and moveable to another position to permit rotation of said spools independently of each other, the weight 60 of said pulley block and its associated parts being sufficient to impart movement to said carriage toward the control-end of the rigging when said travel line is paid out.

9. A toy comprising a part in the form of a 75

pulley block, a part in the form of a supporting carriage for said block, a track element for said carriage, a travel line and a lift line and a trip line, said lift line being rigged to said parts and having one of its ends fixed to one of said parts, means for paying out or taking in said lift line to lower or raise said block with respect to said carriage, said travel line being rigged with respect to said carriage and arranged when paid

out or taken in one side of the carriage to cause the same to travel back and forth along said track element and means for keeping said travel line relatively taut irrespective of any movements of said parts, said last mentioned means comprising a spool suspended between two twisted elastic bands. 5

CHESTER A. PRIDHAM.
